Emil F. Fenner INVENTOR

UNITED STATES PATENT OFFICE.

EMIL F. GENNERT, OF NEW YORK, N. Y.

INSULATING-JOINT.

SPECIFICATION forming part of Letters Patent No. 430,846, dated June 24, 1890.

Application filed November 23, 1889. Serial No. 331,290. (No model.)

To all whom it may concern:

Be it known that I, EMIL F. GENNERT, a citizen of the United States of America, and a resident of the city, county, and State of New York, have invented certain new and useful Improvements in Joints and Couplings for Fixtures for Electric Lighting; of which the following is a specification.

My invention appertains to fixtures for gas or electric lighting, and relates more especially to the joint connecting a fixture to the nipple of a ceiling supply-pipe or support, my object being to provide a joint which will be free to move in any direction to a sufficient extent to allow the fixture to be swung in and to maintain a vertical position, even though the nipple should project at considerable inclination from the vertical, or in the case where said nipple changes direction of projection, as is the case with nipples in the ceilings of the cabins of ships or steamboats, and to provide such a movable joint with means for preventing it from swiveling and with proper insulation, so as to make it suitable for use on combined gas and electric-light fixtures.

My invention consists in the construction, arrangement, and combination of parts whereby I accomplish the aforesaid objects, as is hereinafter described, and particularized in the claims.

In the accompanying drawings, which form part of this specification, Figure 1 shows an elevation partly broken to a central section. Fig. 2 shows a top view of Fig. 1 with part of the nuts and insulation removed. Fig. 3 shows a horizontal section of Fig. 1 on the plane 1 2. Fig. 4 shows an elevation, partly in central section, of a modified form of my invention. Fig. 5 shows a top view of Fig. 4 with part of the annular nut and insulation removed. Fig. 6 shows a horizontal section of Fig. 4 on the plane 3 4. Fig. 7 shows a vertical central section.

Like letters designate like parts in all the figures.

The nipple A, having a screw-thread or other suitable means of connection to a gas or electric-light fixture, is made with a semi-ball-shaped portion *a*, adapted to fit freely but snugly and gas-tight in the semi-spherical chamber of a casing B, which is detachably

joined to another nipple C, that has a screw-thread or other suitable means of connection to a nipple projecting from a line of supply-pipe. The nipple A is diminished in size just below the semi-ball-shaped portion *a*, so as to form a neck, which passes through the lower end of the casing B through an opening sufficiently large in diameter to allow it considerable movement. Lugs G G project downward from the lower end of this casing, and the spaces between these lugs are adapted to receive projections *g g* of any suitable form, which are attached to the nipple A in such a position that the projections of the nipple will engage with the lugs of the casing and prevent the swiveling of the joint, but not prevent movement otherwise, the purpose being to protect any connected electric conductors from being twisted by the accidental turning of the joint.

The casing B may be joined to the nipple C by any suitable means without departing from my invention; but I prefer to constitute of it and the nipple an insulated coupling by means of the annular flanges *b* and *c*, the flange *b* being made to project from the upper end of the casing A, and the flange *c* to project from the lower end of the nipple C.

A washer D of insulating material is placed between them, and another washer of insulating material is placed on the top of the flange *c*, and then bolts F F are passed through both flanges and washers, suitable bolt-holes being provided in each. These bolts are screwed up tight into the nuts or annular nut-plate *f f*, and thus the nipple C and casing A are secured together. The bolt-holes in the flange *c* are made much larger than the diameter of the bolts, and the bolts being passed centrally through them a space *i* is left between them and the flange *c*, thereby avoiding contact of the metal parts and securing a perfect insulation, to assure which I make the insulating-washer *e* with an angular opening through its center that fits snugly on the portion *J* of the nipple C, which portion is provided externally with corresponding angles. This construction, it will be seen, serves to hold the washer *e* in a central position, and also to prevent it from turning around, and as the bolt-holes in it are of the same diameter the bolts are held by it centrally.

the bolt-holes of the flange *c*. The insulating-washer *D*, I make with the two cylindrical flanges *H* and *h* joining its periphery, the flange *H* extending upward to cover the periphery of the metal flange *c*, and the flange *h* extending downward to cover the periphery of the metal flange *b*, the purpose being to prevent contacting of the said flanges with any outside part, such as the canopy sometimes used to cover the joint of a fixture.

I prefer to make the projections *g g* detachable, as the screw-pins shown in Fig. 1, or adjustable, as shown in Fig. 4, in which a band *K*, having the projections *g g*, encircles the nipple *A* and is adapted to adjustment thereon. It is provided with suitable means for securing it in fixed position, so its lugs will engage the lugs *G G* on the casing; but it may be desirable when putting up a fixture to turn the nipple *C* without turning the whole fixture. In such case the detachable or adjustable projections can be disengaged from the lugs, and this will allow the joint to turn till the nipple *C* is screwed to its place, whereupon said projections can be again fixed in position to engage the lugs.

In cases where a ground-current of electricity is needed or desirable an insulated joint is not needed; but it is obvious that an anti-swiveling ball-and-socket joint is useful and important on any pendent fixture, even though it has but one electric conducting-wire. I will therefore make this part of my invention the sole subject of one claim.

Having thus described my invention, what I claim as new, and desire to secure by Letters Patent, is—

1. In fixtures for gas and electric lighting, a ball-and-socket joint consisting of a nipple *A*, having the semi-ball-shaped portion *a*, and provided with projections *g g*, which are external to the casing forming the socket, in combination with the casing forming the socket for said semi-ball-shaped portion *a*, and provided with lugs *G G*, which are adapted to engage with the said external projections *g g* on said nipple, in the manner and for the purpose set forth.

2. In fixtures for gas and electric lighting, an insulated joint consisting of the nipple *C*, having the flange *c*, the casing *B*, constituting the socket of a ball-and-socket joint, having the flange *b* and the lugs *G*, the intervening washer of insulating material *D*, the top washer of insulating material *e*, and the bolts *f f*, in combination with a ball-and-socket joint consisting of the said casing *B*, the semi-ball *a*, fitted therein, as described, the projections *g*, and the nipple *A*, said elements being arranged in the manner and for the purpose set forth.

3. In fixtures for gas or electric lighting, an insulated joint consisting of a nipple, as *C*, having the external angular portion, as *J*, and provided with a flange *c*, having bolt-holes 65 adapted to form annular spaces around the bolts, bolts, as *f*, having suitable nuts, a washer of insulating material, as *e*, having an angular central opening adapted to fit on the portion *J* of the nipple *C* and provided with bolt-holes that fit closely to the bolts, and an intermediate washer of insulating material, as *d*, in combination with a flange, as *b*, having bolt-holes and provided with suitable means to attach a gas or electric fixture, said elements being arranged in the manner and for the purpose set forth.

4. In fixtures for gas and electric lighting, a nipple *C*, adapted for attachment to gas-pipe and having the flange *c*, a casing *B*, having the flange *b*, a nipple *A*, suitably attached to said casing *B* and adapted for attachment to gas-pipe, bolts *F F*, for securing said flanges *c* and *b* together, and a washer of insulating material having an integral cylindrical flange, 85 which serves to cover the peripheral surfaces of said flanges *c* and *b*, as and for the purpose set forth.

In testimony that I claim the foregoing as my invention I have signed my name, in presence of two witnesses, this 22d day of November, 1889.

EMIL F. GENNERT.
